UNITED STATES PATENT OFFICE.

WILLIAM PARKIN, OF TAUNTON, MASSACHUSETTS, ASSIGNOR TO REED & BARTON, OF SAME PLACE.

DESIGN FOR CAKE-DISH.

Specification forming part of Design No. 5,190, dated August 8, 1871.

To all whom it may concern:

Be it known that I, WILLIAM PARKIN, of Taunton, of the county of Bristol and State of Massachusetts, have invented or produced a new ornamental Design for a Cake-Dish or Tazza; and do hereby declare the same to be represented in the accompanying drawing, of which—

Figure 1 is a front elevation of the tazza, and Fig. 2 a front view of one of its lateral male heads in alto-relievo.

The base A is bell-shaped and provided with four clawed feet, *a*, and surmounted by four arms, *b*, which spring from a common prismatic head, *c*. On this head there rests a bird, *d*, having its wings expanded. Each of the arms is sustained

by a ram-headed brace, *e*. The bowl of the tazza shaped as shown, is upheld by the arms, each terminating against one of four heads, *f*, in alto-relievo, arranged on the outer side of the rim of the bowl. The handle *g* springs from two of the heads and is surmounted by the figure of a fox, all being as shown in the drawing.

I claim—

The design, as above explained and represented.

WILLIAM PARKIN.
